UNITED STATES PATENT OFFICE.

IGNACY MOSCICKI, OF LEMBERG, AUSTRIA-HUNGARY.

ELECTRIC FURNACE.

1,201,607

Specification of Letters Patent.

Patented Oct. 17, 1916.

Application filed May 29, 1913. Serial No. 770,676.

To all whom it may concern:

Be it known that I, IGNACY MOSCICKI, a subject of the Emperor of Austria-Hungary, and residing at Lemberg, Austria-Hungary, have invented certain new and useful Improvements in Electric Furnaces, of which the following is a specification.

My invention relates to an electric furnace having a rotating flame for treating gases and vapors.

In known electric furnaces wherein a flame supplied with alternating current rotates under the influence of a magnetic field, that reignition of the flame which is necessary at each reversal of the current usually occurs at that place at which the flame was located at the moment just previous to its extinction and at which a moment afterward there will still be ionized gases. It often happens, however, that just at the moment the current has its zero value the ionized gases are expelled under the influence of a surge of gas, and reignition of the flame then becomes an exceedingly troublesome matter. In order nevertheless to maintain the furnace in continual operation, it is necessary to employ a higher voltage and to work with a larger phase displacement than would be required did this phenomenon not occur, and consequently the current is utilized in a very disadvantageous manner.

It has already been proposed to provide one electrode with a tongue or lug, whereby the distance between the electrodes is diminished at one place in the reaction chamber, and at this place the reformation of the flame is favored, but this tongue or lug has the disadvantage that the flame remains too long at this place of nearest approach of the electrodes as compared with the period of one alternation. It has however been impossible in practice to increase the intensity of the field under whose influence the flame rotates sufficiently to drive the flame, each time it forms, quickly enough from the ignition tongue. Consequently a difficulty arose in maintaining a large load in the furnace, because as long as the flame is short the fall of potential across it is smaller than when the flame is extended to its normal length.

A primary object of my invention is to obviate the above defects and to provide a furnace wherein the formation of surges of

gas has no detrimental influence on the re- 55 ignition of the flame, and wherein there are none of the disadvantages resulting from employing a tongue.

Several illustrative embodiments of my invention are represented by way of example in the accompanying drawing, where-

in:

Figure 1 is a sectional elevation showing one form of my improved furnace, and Fig. 2 is a section taken on the line II-II in 65 Fig. 1; Fig. 3 is a sectional elevation showing a second form of furnace, and Fig. 4 is a detail view relating to the above forms; Fig. 5 is a sectional elevation showing a portion of a third form of furnace; Figs. 70 6 and 7 are sectional elevation and plan, respectively showing a portion of the electrodes in a fourth form of furnace, and Figs. 8 and 9 are like views of parts of a fifth form of furnace.

Referring to the drawings, the reaction-chamber 1 (Fig. 1) is connected below with a conical supply-chamber 2 which increases in diameter downwardly and receives the gases from the supply pipe 3. At the junction between the two chambers, *i. e.* where the gases from the supply-chamber enter the reaction-chamber, the wall of the former chamber has an annular edge 13. To the top of the reaction-chamber 1 is connected 85 the cooling duct 4, through which the gases pass to the discharge-pipe 5. Both the reaction-chamber and cooling-duct are inclosed in a cylindrical vessel 6, through which can flow the cooling liquid which enters by the pipe 7 and leaves by the pipe 8. An outlet 9 is provided for steam or vapor. The vessel 6 is surrounded by a coil 10 which serves for producing a strong magnetic field. Extending upwardly into the reaction-chamber 95 1 is the conical end of a concentrically disposed, axially displaceable electrode 12 which is provided with a cooling device. The free end of this electrode is in close proximity to the annular edge 13. The gap 100 between the electrode 12 and the edge 13 can be varied by vertically displacing the electrode 12, and is made of such a width that, at each reversal of the current, reignition occurs at the place where the electrode 12 and the edge 13 are closest. When the furnace is in operation, the high-tension flame at the moment of its formation is

forced toward the free end of the central electrode owing to the very high speed (50 and 100 m. and more per second) at which the gases flow between the central electrode 5 12 and the edge 13 in close proximity therewith, and is simultaneously set rotating under the influence of the strong magnetic field. At the very moment at which the form of the flame begins to assume that of an arc, 10 that component of the electro-magnetic force is formed which tends to set the level of the arc instantly at right angles to the magnetic lines of force, and which compels the outer end of the flame to travel quickly from the 15 lower closure plate of the furnace to the periphery thereof. Owing to the simultaneous action of these two factors, after each alternation the flame is considerably lengthened in a very short time compared with the 20 period of one alternation of the current, and this enables the furnace to be more highly loaded. By suitably choosing the diameter of the central electrode, the area of the passage at the level of the ignition edge can be 25 made such that with a given supply of gas the desired high velocity of flow of the gases is obtained in this passage.

For the regular operation of the furnace it is very important that the ignition of the 30 flame following each reversal of the current shall take place only in the annular gap for ignition. Consequently, the electrical disruptive strength of the gaseous dielectric at the moment of each ignition of the flame between the ignition edge 13 and the central electrode should be smaller than the disruptive strength of this dielectric at another place, *e. g.*, at the place where there are ionized traces of the extinct flame. The 40 conical form of the middle electrode while permitting the distance of the electrode from the ignition edge to be regulated within wide limits, enables the above-named requirements to be very readily satisfied.

45 In the embodiments illustrated in Fig. 3 the reaction-chamber 1 is located between two magnet-poles 14, 15, which produce a very strong magnetic field. Owing to the central opening *b* in the pole 15, the magnetic lines diverge in the lower portion of the reaction-chamber and at the place where the flame is ignited. Consequently, the outer end of the flame is more quickly driven to the periphery than in the furnace illustrated 55 in Fig. 1.

If the voltage employed for the furnace is comparatively low, and the ignition-gap therefore narrow, and if at the same time the energy expended in the furnace is large, 60 in order to be able to supply sufficient gas to the flame it is necessary to introduce it at a correspondingly higher pressure. To avoid the extra expense in working thus involved, inlets for a portion of the gases can 65 be arranged directly in the reaction-cham-

ber, whereby only a portion of the gases passes through the gap. This is not, however, a very satisfactory mode of operation.

It is preferable to maintain the width of the annular gap and simultaneously to enlarge the area of the passage therethrough by giving this gap a larger diameter. If required, this diameter can be increased to such an extent that the outer electrode, instead of being narrowed, forms the ignition 70 edge. If, as in the embodiment shown in Fig. 5, the diameter of the inner electrode 12 is large as compared with the diameter of the reaction-chamber 1 which is here arranged below the electrode for a reason 80 hereinafter explained, the inner electrode will have an active face which rises only slightly in the middle, in order that after each reversal of the current small displacements of the flame in the direction of its 85 axis of rotation may cause considerable increases in the length of the track swept by the flame, and the latter therefore obtains a very great length as quickly as possible. 90

Instead of obtaining the necessary increase in the area of the passage for the gases by increasing the diameter of the ring, the annular edge 13 may have uniformly distributed indentations 18, as shown in Figs. 6 and 7. The inner electrode may 95 also have indentations uniformly distributed around it. Since the uniform supply of the gases is not impaired by the indentations and grooves, this mode of obtaining an increased area of passage has much in its 100 favor. When a uniform supply of gas is not so important, the diameter of the annular edge can be made somewhat greater and the inner electrode arranged eccentrically within it (Figs. 8 and 9). Both when 105 employing indentations or grooves in the annular edge and outer electrode, and when arranging the inner electrode eccentrically, it is important to make the gas-pressure in the gap such that even at the narrowest portion of the latter the velocity is sufficient 110 instantly to drive the flame in the axial direction.

In the embodiment shown in Fig. 4, the ignition edge 13 of the furnace is carried 115 by an exchangeable member, which is fastened in place by a ring 16 and has an inlet and an outlet for the cooling liquid. Consequently, that part of the outer electrode which is exposed to the greatest wear 120 can be exchanged.

In furnaces working with a comparatively low voltage, and consequently requiring a very small distance between the annular ignition edge and the central electrode, it is 125 preferable to invert the arrangement shown in Figs. 1 and 3, *i. e.* to arrange the apparatus as in Figs. 5, 6 and 8, wherein the supply chamber is located above the reaction-chamber and the gases flow downward 130

through the flame. It is thereby avoided that the metallic oxid which forms can eventually fall into the gap between the central electrode and the ignition edge and 5 so cause irregularities in working.

I claim:—

1. An electric furnace for the treatment of gases and vapors, in which furnace a high-tension, alternating-current flame rotates under the influence of a magnetic field of force, said furnace having an outer electrode within which is inclosed the reaction chamber; an inner electrode that projects thereinto, the interval between said electrodes measured in the direction of the flow of the gas increasing very rapidly; the inner electrode being arranged free to be shifted and to be adjusted relatively to the outer electrode in such manner that the ignition-ring remaining free between the electrodes can be adjusted exactly to the tension of the working current so as to be able first to generate the flame at said ring at every current reversal and then, under the influence of the powerful magnetic field and the great velocity of the gases, to draw the flame out to a great length and absolutely within a small fraction of the period of a single alternation.
2. An electric furnace for the treatment of gases and vapors, in which furnace a high-tension, alternating-current flame rotates under the influence of a magnetic field of force, said furnace having an outer electrode within which is inclosed the reaction chamber; an inner electrode that projects thereinto; the interval between said electrodes measured in the direction of flow of the gases increasing very rapidly and one of the electrodes being formed with indentations in order, in case the inner electrode is of small diameter, to furnish a sufficient passage-cross-section for the gases in spite of the small breadth of gap; the inner electrodes being arranged free to be shifted and to be adjusted relatively to the outer electrode in such manner that the ignition ring remaining free between the electrodes can be adjusted exactly to the tension of the working current so as to be able first to generate the flame at said ring at every current reversal and then, under the influence of the powerful magnetic field and the great velocity of the gases, to draw the flame out to a great length and absolutely within a small fraction of the period of a single alternation.
3. An electric furnace for the treatment

of gases and vapors, in which furnace a high-tension, alternating-current flame rotates under the influence of a magnetic field of force, said furnace having an outer electrode within which is inclosed the reaction chamber; an inner electrode that projects thereinto and is arranged eccentrically to the outer electrode, the interval between said electrodes measured in the direction of flow of the gases increasing very rapidly; the inner electrode being arranged free to be shifted and to be adjusted relatively to the outer electrode in such manner that the ignition-ring remaining free between the electrodes can be adjusted exactly to the tension of the working current so as to be able first to generate the flame at said ring at every current reversal and then, under the influence of the powerful magnetic field and the great velocity of the gases, to draw the flame out to a great length and absolutely within a small fraction of the period of a single alternation.

4. An electric furnace for the treatment of gases and vapors, in which furnace a high-tension, alternating-current flame rotates under the influence of a magnetic field of force, said furnace having an outer electrode within which is inclosed the reaction chamber; an inner electrode that projects thereinto; a hollow ring which is detachably fastened to the outer electrode so as to be readily exchangeable and is provided with an ignition-edge inclined toward the inner electrode and is arranged for the passage of a cooling medium; the interval between said electrodes measured in the direction of flow of the gases increasing very rapidly; the inner electrode being arranged free to be shifted and to be adjusted relatively to the outer electrode in such manner that the ignition-ring remaining free between the electrodes can be adjusted exactly to the tension of the working current so as to be able first to generate the flame at said ring at every current reversal and then, under the influence of the powerful magnetic field and the great velocity of the gases, to draw the flame out to a great length and absolutely within a small fraction of the period of a single alternation.

In testimony whereof, I affix my signature in the presence of two witnesses.

IGNACY MOSCICKI.
